ELASTIC FLUID CONDENSER ARRANGE-
MENTKarl Schmer, Berlin-Mariendorf, Germany, as-
signor to General Electric Company, a corpora-
tion of New YorkApplication June 29, 1937, Serial No. 151,019
In Germany July 4, 1936

3 Claims. (Cl. 60—95)

The present invention relates to elastic condenser arrangement for condensing elastic fluid discharged from prime movers and is of special significance in connection with locomotive power plants.

The object of my invention is to provide an improved construction and arrangement of elastic fluid condenser arrangements which permit effective operation.

For a consideration of what I believe to be novel and my invention, attention is directed to the following description and the claims appended thereto in connection with the accompanying drawing.

The single figure of the drawing represents a diagrammatic view of an elastic fluid condensing arrangement in connection with steam turbine power plants as may be used for operating locomotives.

The arrangement in the drawing comprises a boiler 10 of the single tube, forced-through type including a heating element 11 and a burner 12 having an inlet conduit 13 for fuel and another inlet conduit 14 for air for maintaining combustion in the boiler. Operating medium, such as water, contained in a tank 15 is forced through the heating tube 11 by means including the boiler feed pump 16. Elastic fluid discharged from the boiler is conducted through a conduit 17 to a prime mover, in the present instance a turbine 18. The exhaust of the turbine is condensed in a condenser 19. The condensate is discharged into the aforementioned tank 15. The condenser 19 is a surface type heat exchanger with a cooling element 20 through which cooling medium is passed to effect condensation of the exhaust from the turbine.

In order to permit condensation by means of a comparatively small condenser and to prevent loss of condensing or cooling medium, I provide in accordance with my invention a closed system which includes an air-cooled, surface type heat exchanger and a reservoir for cooling liquid connected in series with the cooling element 20 of the condenser 19. More specifically, the arrangement comprises a reservoir or tank 21 for cooling medium, preferably water, connected to the outlet of the cooling element 20 by a conduit 22 to receive heated cooling medium discharged from the cooling element 20. The tank 21 in turn discharges the heated cooling medium through a conduit 23 and a circulating pump 24 to a surface-type heat exchanger 25 which in turn is connected by a conduit 26 to the inlet of the cooling element 20. The surface-type, air-

cooled heat exchanger 25 comprises a casing 27 and a plurality of tubes 28 connected between headers 29 and 30. A blower or fan 31 driven by a variable speed motor 32 is provided for forcing cooling air across the tubes 28. The motor 32 is connected through a variable resistance 33 to the source of electric energy 34.

During operation a continuous circulation of cooling medium through the cooling circuit including the heat exchanger 25, the cooling element 20 and the pump 24 is effected. The cooling effect of the heat exchanger 25 may be controlled by adjusting the speed of the variable speed motor 32. This control may be effected automatically in response to changes of the temperature of the cooling fluid discharged from the cooling element 20. To this end I provide in the present instance a temperature responsive device 35 for varying the resistance 33 in response to temperature changes. With the arrangement shown the speed of the motor 32 is increased in response to increasing temperature in the conduit 23 to effect increased flow of cooling air across the heat exchanger tubes 28. By arranging the temperature responsive device 35 in thermal communication with the conduit 23 at the outlet of the tank 21, the control of the motor 32 is materially stabilized. The temperature of the cooling medium flowing from the cooling element 20 of the condenser will be subject to sudden fluctuations in temperature depending upon the nature of the load connected to the prime mover 18. Such temporary conditions of the cooling medium temperature will be smoothed out in the tank 21 so that the thermal responsive device and hence the motor 32 will be regulated in accordance with the major changes in the operating conditions of the system. The heat transferred from the exhaust fluid of the turbine to the cooling medium is utilized in accordance with my invention by the provision of a heater 36 connected in parallel to a portion of the conduit 23. The heater may serve for heating the cars connected to a locomotive. The arrangement shown in the present instance includes three valves 37, 38, and 39. With the valves 38 and 39 closed and the valve 37 open, all of the liquid discharged by the pump 24 is forced directly into the heat exchanger 25. Vice-versa, with the valve 37 closed and the valves 38, 39 open, the heated liquid discharged by the pump 24 first flows through the heater 36 before it enters the heat exchanger 25. The heat transmitted from the tubes 28 of the heat exchanger to the cooling air passing across

these tubes is also at least partly utilized. In the present instance a part of the air discharged from the heat exchanger 25 is forced through a conduit 40 including a valve 41 and a blower 42 into the air inlet conduit 14 of the burner 21. Another part of the air is conducted through a conduit 43 to be discharged therefrom to a consumer such as an air heater, not shown. As the cooling medium for effecting condensation in the 10 turbine condenser is contained in a closed system, loss of cooling medium is eliminated which is a great advantage, especially when the arrangement is to be used in connection with vehicles. The provision of a water-cooled, surface-type turbine condenser as pointed out above reduces considerably the dimensions of such condensers, an important point to be considered especially in locomotive design. The surface-type heat exchanger 25 is also of comparatively small 15 dimensions in view of the good heat transfer between water and air. This makes it possible to arrange the heat exchanger 25 so that its air resistance becomes comparatively small. The elements of the cooling circuit being connected by 20 conduits 22, 23 and 26 may be arranged in any desirable manner.

From the standpoint of thermal economy it is permissible to provide a condenser either with a small vacuum or with no vacuum at all since 25 boilers are now available for generating steam or other elastic fluid of high pressure and a high degree of superheat. In some cases it is advantageous to circulate the cooling water slowly, that is, to discharge it from the heating element 30 20 at a high temperature. Such arrangement permits efficient heating of cars connected to a locomotive and no longer makes it necessary to withdraw steam from the boiler for heating purposes. Live steam then will be used at the most 35 40 for the initial heating of a train when it is standing still.

Having described the method of operation of my invention, together with the apparatus which I now consider to represent the best embodiment

thereof, I desire to have it understood that the apparatus shown is only illustrative and that the invention may be carried out by other means.

What I claim as new and desire to secure by Letters Patent of the United States, is:—

1. Elastic fluid condenser arrangement including the combination of a condenser having a cooling element, a tank connected to the cooling element, a surface type heat exchanger and a pump connected in series with the tank and the 10 cooling element, and means for forcing air into the surface type heat exchanger and automatically variably adjusting the flow of air in response to temperature conditions of the cooling medium at the outlet of said tank. 15

2. Elastic fluid condenser arrangement including the combination of a condenser having a cooling element, a tank connected to the cooling element, a surface type heat exchanger and a pump connected in series with the tank the cooling element, and heating means utilizing available heat energy of the cooling medium discharged from the cooling element, means for controlling the flow of said cooling medium through said heating means and means for utilizing air discharged from said heat exchanger including means for conducting a portion of said discharged air to a boiler to maintain combustion therein. 20 25

3. Elastic fluid condenser arrangement including the combination of a condenser having a cooling element, a tank connected to the cooling element, a surface type heat exchanger and a pump connected in series with the tank and the cooling element, means for forcing air into the 30 surface type heat exchanger and automatically adjusting the flow of air in response to temperature conditions of the cooling medium between said tank and said heat exchanger, and means for conducting a portion of the air discharged from the heat exchanger to a boiler to maintain combustion therein. 35 40
